MULTIPURPOSE FORK TRUCK

Otto J. Gerhardt, Yakima, Wash., assignor to
Valley Evaporating Company, Yakima, Wash.

Application May 12, 1952, Serial No. 287,274

4 Claims. (Cl. 214—653)

1

My invention relates to industrial trucks, and more particularly, to a multipurpose fork truck. Briefly the improvement includes a pair of fork arms, mounted to rotate about an axis normal to the carriage of the fork truck, having elongated flat working faces lockable in a position extending horizontally or positionable in an upright plane or in a diagonal plane. Means are provided to move the fork arms toward and away from each other. In this way the fork truck is easily adjustable to various types of load-carrying functions.

In recent years the fork truck has become a common adjunct to most industries and has resulted in considerable economy. Various types of fork trucks have been designed for particular industries. Generally these fork trucks have been adapted for only one type of load-carrying action unless the fork assembly is taken apart and put together in a different relationship, often with different parts. It is deemed important to many industries, particularly small plants, to have a multipurpose fork truck which may be readily changed from one to the other of the most common types of load carrying actions. The three most common actions are with the load-carrying faces of the fork arms horizontal, with the faces upright including means to squeeze the opposed faces together, and with the faces in diagonal plane as is useful in carrying round objects such as barrels.

The objects of my invention include therefore: to provide a multipurpose fork truck which is readily adjustable for various uses; to devise a fork truck readily adaptable to dispose the working faces of the fork arms in the three most common positions, e. g., in a horizontal plane, in an upright plane, and in a diagonal plane; and to provide an adaptable fork truck of economical construction for use in small plants.

My invention will be best understood, together with additional objects and advantages, from the following description, when read with reference to the drawings, in which:

Figure 1 is a perspective view, partly in section, of the fork arms assembly and carriage of a specific embodiment of my fork truck;

Figure 2 is a side view of the fork truck, with certain parts broken away;

Figure 3 is an elevational view looking at the front of the fork arms assembly;

Figure 4 is a view, partly in section, taken generally on line 4—4 of Figure 3;

Figure 5 is a view, partly in section, of the means for supporting and moving the fork arms carrying plates;

2

Figure 6 is a view from the side, partly in section, of the structure shown in Figure 5; and

Figure 7 is a perspective view, in fragmentary form and partly in section, showing the rack means of the fork arm operating assembly.

The conventional fork truck construction is well known and the description herein will generally be limited to those things which are changed from the ordinary construction. In Figure 2 is shown the fork truck body B of conventional construction. The fork arms assembly is vertically movable on the stationary vertical guide members 10 of channel construction. Vertically movable on guide members 10, by conventional means, is a pair of vertical carriage members 12 which are likewise channel-shaped.

Attached to carriage 12 are two pairs of hollow cylindrical guideway members 14 and positioned within these cylindrical guideways are corresponding cylindrical slide members 16. These slide members support the fork arms supporting plates 20, the connection between the same being by means of connecting plates 22 welded to supporting plates 20 and secured in slots 24 in each cylindrical slide member 16. Connecting plates 22 operate in slots 26 in hollow guideway members 14. It will be observed from this construction that fork arm supporting plates 20 are securely supported and are movable horizontally toward and away from each other. The operating means for this action comprise hydraulic cylinder 30 and piston members 32 positioned in cylinder 30 and secured to fork arms supporting plates 20 by flanges 34. Fluid under pressure introduced into hydraulic cylinder 30, through line 36 between pistons 32 moves the supporting plates 20 apart and fluid introduced to the other side of the pistons through lines 38 brings them together for the squeezing movement of the fork arms in the position shown in Figure 1.

To insure that the supporting plates 20 move the same distance in outward and inward movement, a rack and pinion assembly acts between the lowermost cylindrical slide members 16. This assembly includes pinion 40 journalled in the protective plates 42 and 44 and engaging the rack means in the slide members, as shown in Figure 7. The rack means include the longitudinal recesses 46 in each lower cylindrical member 16 and the chain 48 engaging pinion 40 and acting as a rack. Chain 48 is secured in recess 46 by pins 50 passing into chain 48 in the openings provided for the chain pins. It will be observed that this is an economical method of constructing the racks.

Secured to each fork arm supporting plate 20

is a vertical load-supporting angle iron 51 and secured to guideway members 14 is a vertical load-supporting channel 52.

Extending outward normal to fork arm supporting plates 20 are fork arms 60, each having a flat elongated working face 62 strengthened on the opposite side by reinforcing ribs 64. Each supporting plate 20 has a circular opening 70 in which are rotatably mounted circular guide plates 72. The axis of rotation of circular plates 72 runs parallel to working faces 62 of fork arms 60 on a line spaced therefrom to the end that fork arms 60 in their horizontal disposition, shown in full lines in Figure 3, tend to remain in that orientation. On the inside of circular guide plate 72 is a cheek plate 74 inset into supporting plate 20 and lapping the edges of opening 70; and, formed integral with fork arm 62, is lateral portion 76 lapping the edges of opening 70 and acting in the manner of a cheek plate. Cheek plates 74, 76 and circular guide plate 72 are secured together by a series of bolts and nuts 78. Fork arm supporting plates 20 have raised working faces 79 flush with the surfaces of lateral cheek plate portions 76.

Two of the positions which fork arms 60 may assume are shown in Figure 3, the working faces 62 being shown disposed horizontally in full lines, and in dotted lines being shown disposed in diagonal planes. In the horizontal position pallets and the like may be handled and supported from below. As supporting plates 20 are movable horizontally, fork arms 60 may be positioned at various distances apart, which is a valuable feature in handling various pallets or loads where it is desirable to have the fork arms a certain distance apart. The fork arms are positioned diagonally carrying such objects as barrels, paper rolls, and the like and again it is important to have means for positioning the fork arms at various distances apart for carrying circular bodies of various diameters. In neither of these positions is it necessary to have means for securing the fork arms in position as they naturally assume their position in load-carrying partially because the axes of rotation of plates 72 are spaced from working faces 62. In Figure 1 the working faces 62 are shown disposed in an upright plane. This is the position of carrying objects such as are shown in Figure 2 which are not on pallets. The hydraulic assembly 30, 32, exerts pressure on the fork arms to grip the object as shown in Figure 2. It is desirable in this position to have the fork arms locked in place and this is accomplished by pawls 80 acting in notches 82. Bolts 78, securing together the cheek plates, are usually tensioned to prevent easy rotation of the fork arms, and a tool carried on the fork truck in the form of a crowbar having a bifurcated end is commonly used to engage the fork arms to move them from one position to another. In this way the fork trucks can be changed from one type of use to another by an adjustment taking a few seconds of time.

In the preferred construction of my device the working faces 62 of arms 60 are firm rubber pads 63 approximately one-half inch thick which, particularly when the arms grip a load, engage the load faces with a resilient, non-slipping and non-marring action. Such rubber pads 63 are indicated by the double line showing of the jaw faces.

Having thus described my invention, I claim:

1. A fork truck assembly, comprising: a vertically movable fork carriage; a pair of fork arm supporting members connected to said carriage

and movable transversely thereof in a horizontal direction; a pair of fork arms each having an elongated broad working face and each extending outward from one of said supporting members normally thereto, each supporting member having a circular opening therein and a broad circular guide plate rotatably mounted therein and a cheek plate secured to the rear face of said guide plate and lapping the edges of said opening and each fork arm having an integral cheek plate portion comprising a crank arm extending laterally from said working face and secured in overlying relation to the front face of its guide plate and lapping the edges of said opening whereby said fork arm is offset from the axis of said guide plate; and locking means between each supporting plate and its fork arm for securing the latter when its working face is upright.

2. The subject matter of claim 1 in which the locking means comprises a pawl pivotally connected to each fork arm supporting member and each cheek plate portion of each fork arm has a notch positioned to be engaged by the adjacent pawl when the working face of the fork arm is positioned in an upright plane.

3. A fork truck assembly, comprising: a vertically movable fork carriage; a pair of fork arm supporting members connected to said carriage and movable transversely of said fork carriage in a horizontal direction and means for moving said supporting members toward and away from each other; a pair of fork arms, each extending outward from one of said supporting members normal thereto and having its inner end secured to its supporting member by means of a journalled crank in a manner permitting rotation of the fork arm about an axis extending normal to its supporting member and offset from the axis of the crank arm journal, a plurality of horizontally disposed hollow guideway members secured to said fork carriage and at least one horizontally disposed slide member secured to each fork arm supporting member and positioned in one of said hollow guideway members for supporting said supporting member in its movement relative said fork carriage and a pair of facing racks, one on a slide member of each fork arm supporting member and a pinion engaging said racks and fixedly secured in relation to said fork carriage insuring that said supporting members move toward and away from each other the same distance from the center of said carriage.

4. A fork truck assembly, comprising: a vertically movable fork carriage; a pair of fork arm supporting members connected to said carriage and movable transversely of said fork carriage in a horizontal direction and means for moving said supporting members toward and away from each other; a pair of fork arms, each extending outward from one of said supporting members normal thereto and having its inner end secured to its supporting member in a manner permitting rotation of the fork arm about an axis extending normal to its supporting member, a plurality of horizontally disposed hollow guideway members secured to said fork carriage and at least one horizontally disposed slide member secured to each fork arm supporting member and positioned in one of said hollow guideway members for supporting said supporting member in its movement relative said fork carriage and a pair of facing racks, one on a slide member of each fork arm supporting member and a pinion engaging said racks and fixedly secured in relation to said fork carriage insuring that said supporting members

move toward and away from each other the same distance from the center of said carriage, said slide members carrying said racks being cylindrical and having longitudinal recesses and having chains secured in said recesses forming said racks.

OTTO J. GERHARDT.
